UNITED STATES PATENT OFFICE.

CHARLES J. PILLING, OF PHILADELPHIA, PENNSYLVANIA, ASSIGNOR TO
HIMSELF AND GEORGE P. PILLING, OF SAME PLACE.

DESIGN FOR A SUPPORTING MEMBER FOR VAGINAL RETRACTING-SPECULARS.

SPECIFICATION forming part of Design No. 31,396, dated August 15, 1899.

Application filed July 18, 1899. Serial No. 724,313. Term of patent 7 years.

To all whom it may concern:

Be it known that I, CHARLES J. PILLING, a citizen of the United States, residing at the city of Philadelphia, Pennsylvania, have invented a certain new and original Design for a Supporting Member for a Vaginal Retracting-Specular, of which the following is a full, clear, and exact description, reference being had to the accompanying drawings, forming a part 10 of this specification.

My invention relates to the form or configuration of a separable portion of a certain surgical instrument; and it consists in the novel external shape or configuration of the 15 supporting member of a vaginal retracting-specular.

The design is shown in the drawings, in which—

Figure 1 is a perspective view and Fig. 2 20 a vertical section through the longitudinal center.

The body of the member is essentially hollow in form, as shown in Fig. 1 and as indicated by the light line in the sectional figure. At its extreme lower end it is curved or bent 25 outwardly at *b*, and centrally in its vertical portion it is hollow-ribbed at *c*, with one or more screw holes or openings *d d* therein.

Having thus described my invention, what I claim as new, and desire to secure by Letters 30 Patent, is—

The design for the supporting member of a vaginal retracting-specular, substantially as shown and described.

In testimony whereof I have hereunto affixed my signature this 15th day of July, A. D. 35 1899.

CHARLES J. PILLING.
